UNITED STATES PATENT OFFICE

142,101

DESIGN FOR A LOCOMOTIVE BODY

John Markestein, North Riverside, Ill., assignor to General Motors Corporation, Detroit, Mich., a corporation of Delaware

Application June 15, 1945, Serial No. 120,114

Term of patent 14 years

(Cl. D66—1)

To all whom it may concern:

Be it known that I, John Markestein, a citizen of the United States, being a resident of North Riverside, county of Cook, State of Illinois, have invented a new, original, and ornamental Design for a Locomotive Body, of which the following is a specification, reference being made to the accompanying drawing forming a part thereof.

In the drawing:

Fig. 1 is a side elevational view of a locomotive body showing my design.

Fig. 2 is a front elevational view.

Fig. 3 is a perspective view, as seen from a point in front of and at the side of the body.

The appearance of the side of the body opposite to that shown is substantially the same as that shown, and the rear end portion of the locomotive body design is conventional.

I claim:

The ornamental design for a locomotive body, substantially as shown and described.

JOHN MARKESTEIN.
